(57) **CLAIM**

The ornamental design for a golf bag storage pocket, as shown and described.

DESCRIPTION

FIG. 1 is a front elevational view of a golf bag storage pocket showing our new design;

FIG. 2 is a side elevational view of the golf bag storage pocket taken from the left in FIG. 1;

FIG. 3 is a side elevational view of the golf bag storage pocket taken from the right in FIG. 1;

FIG. 4 is a bottom view of the golf bag storage pocket of FIG. 1;

FIG. 5 is a top view of the golf bag storage pocket of FIG. 1; and,

FIG. 6 is a rear elevational view of the golf bag storage pocket of FIG. 1.

The broken line showing of portions of a golf bag is for illustrative purposes only and forms no part of the claimed design.
